Primary Examiner — Nathaniel D. Buckner

(74) Attorney, Agent, or Firm — Collard & Roe, P.C.

(57) **CLAIM**

The ornamental design for connector assembly, as shown and described.

DESCRIPTION

1. Connector assembly

1.1 is a top right perspective view of a connector assembly showing my new design;

1.2 is a Front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof.
